PROCESS OF COLORING PAPER

Pierre Drewsen, Sandusky, Ohio, assignor to
The Hinde & Dauch Paper Company, San-
dusky, Ohio, a corporation of Ohio

Application May 6, 1935, Serial No. 20,102

7 Claims. (Cl. 101—153)

The invention relates to methods of coloring paper and producing colored design effects on the surface of the paper. It is the object of the invention to obtain a process which while applicable to paper in general, is particularly adapted for the coloring of paper to be used in the manufacture of corrugated paper and solid fiber boxes, merchandise display stands, display materials and the like. To this end the invention consists in 10 the novel process as hereinafter set forth.

In the drawing:

Fig. 1 is a diagram illustrating an apparatus adapted for the carrying out of my improved method;

15 Fig. 2 is an enlarged view of Fig. 1;

Fig. 3 is a perspective view thereof.

In the present state of the art there are a number of methods of coloring paper, and of producing colored design effects, and of coating 20 paper. For ordinary purposes, paper is colored in the paper mill. In this process aniline dyestuffs or colored pigments are added to the paper pulp in the beater, and after adding the necessary rosin size and alum, the stock is jordanized and 25 formed into a sheet on the paper machine. There are a number of disadvantages in this method. In the first place, particularly where deep color effects are desired, a considerable portion of the coloring material used is lost in the mill effluent. 30 When changing from one color to another, particularly from a darker to a less dark shade, it is often necessary to shut down the mill and thoroughly wash all chests, beaters, pipe lines, vats, etc. The time, labor and overhead elements involved make the production of small quantities 35 of colored paper economically impossible in most cases. Another serious disadvantage of coloring paper in a paper mill is the problem of trim. Each paper machine has a maximum width of sheet 40 which it may produce. If, for example, an order is received for green liner board which must be say 50 inches wide, to be run on a paper machine which trims 80 inches, it is necessary to make a sheet of green paper 80 inches wide, and then trim 45 out a roll or rolls 50 inches wide, leaving rolls of green paper 30 inches wide. These, having no immediate utility, are placed in storage, where they may stay indefinitely. It is obvious that under present operating conditions, it would not 50 be long before any mill attempting to supply colored boxes or other grades of colored paper would soon be faced with a serious accumulation of odd sized material which would impound working capital. Another disadvantage of paper mill 55 coloring is the practical inability of a mill to fur-

nish a sheet of colored paper which has a surface different from the ordinary grade of paper, for example, a surface with gloss or sparkle. Another disadvantage is the relative inability of a paper mill to color paper on one side only, as is often desired, as for instance, for display purposes. It is true that calender coloring is frequently done in paper mills, but when a water or a water solution is applied to a sheet going through the calender stacks, under the pressure 10 exerted by the heavy stack of rolls, the tendency is to give the sheet a water finish, that is to say, a glazed effect, which for some purposes is not desirable. The principal objections to paper mill coloring, then, are the limited effects obtainable, 15 and the relative inability of the mill to furnish paper in small quantities of the proper color or design without prohibitive loss of time for wash-ups and shutdowns, and without impounding working capital in slow moving or unprofitable 20 lines of odd sizes. Generally speaking, design effects in color are not obtainable on a paper machine.

Another method of coloring or otherwise changing the surface of paper is the well known coating process. In this process, paper is passed through a machine in which a liquid mixture of casein, china clay and aniline dye stuffs is applied to one or both surfaces of the sheet, after which it is dried, and then calendered. The machines for this purpose consist of rollers for applying the liquid mixture, after which the liquid mixture is spread over the surface of the paper by means of camel's hair brushes. Equipment of this character, especially the chemical rooms, the 35 machine rooms, drying rooms, calender rooms, etc., are large, and the operation requires considerable space. In general, the coating process aims rather to produce a fine surface for printing, the coloring being more or less incidental 40 and limited to delicate tints, heavy or deep colors being largely avoided. The coating process is used largely for magazine cover stocks, and certain grades of book paper.

Colored design effects may be produced by 45 printing presses and printing inks. In general, there are three types of printing; the raised letter type, in which the impression is made by portions of the surface of the printing element which is elevated above the surface of the roller or 50 plate; offset printing, in which the effect is produced by the contact of a flat surface with the paper, the ink being delivered to the flat surface first, and finally, there is the so-called intaglio process in which the impression is made 55

by an engraved roller. In this latter process, the engraved roller, usually of copper, rotates in an ink pan, usually called the fountain, and thereby picks up a film of ink over its entire surface. 5 Before it comes in contact with the paper, however, the surplus ink is scraped off by means of a doctor blade, so that the only ink which is left on the copper roller is that included in the depressions of the engraving. The paper, being 10 brought in contact with the copper roller by means of another roller above it picks up the ink from the copper roller, and thereby receives the color impression. In the intaglio process, either 15 flat colors may be imparted to the paper surface, or designs of various sorts may be printed. Sometimes two or more copper rollers are used, each one of which employs a different color, and each of which registers with the others, so that a 20 multi-colored design is produced in the paper. 25 For the purpose of this application, however, we are not concerned with multi-colored effects.

The intaglio process is not particularly satisfactory for printing or coloring or coating liner board. Liner board is made largely from waste 30 paper material, and the rolls of liner board, as received from the paper mill, contain considerable quantities of dust or other impurities which concentrate in the ink fountain, and these dust particles gradually work their way up under the 35 doctor blade which results in streaking the paper and spoiling the product. Inasmuch as the copper roller with the engraving on it is a relatively delicate surface, there is no practical method of cleaning out the dirt from under the doctor blade without injuring the copper surface. If 40 the machine is shut down, there is an interruption of production, and the spoilage of a considerable quantity of paper, and even after the doctor blade is cleaned out, no solution of this problem is offered, because the doctor blade will immediately become fouled again.

I have found that the defects above described can be overcome by removing the doctor blade and permitting the coloring material to be carried 45 up by the fountain roller to the surface of the paper strip in advance of the passage of the same into contact with the knurled or engraved surface. This has the effect of flooding the surface with 50 coloring material, after which the surplus material is squeezed out, leaving only that which is in the depressions in the engraved roller for deposit on the surface of the paper together with a lighter color background on the intermediate unengraved portions. I have discovered that 55 with this method dust or impurities carried by the paper will not accumulate or cause any streaking or smearing of the colored surface. It is, however, desirable to modify the apparatus from the construction employing a doctor blade, as hereinafter set forth.

As illustrated in Fig. 1, A is the roll of paper to be colored from which the strip passes around friction bars B to place thereon the desired tension, after which it passes over a pair of rollers 60 C intermediate which is arranged a steam jet tube D directed against the under surface of the strip. From the roller C the strip passes around a roller E having a plane, unyielding surface, preferably of steel, then around a roller F, the 65 surface of which is formed of rubber or other resilient material and which is pressed in contact with a roller G which has the engraved or serrated surface. The latter roller has a portion of its surface immersed in the color fountain H 70 and when rotating and moving the paper web 75

will carry the coloring material up on one side into the trough formed between this roller and the roller F. This will flood the surface of the paper which is passing around the roller F and will also fill all of the depressions in the engraved surface. Thus as the web passes between the rollers F and G, all of the surplus colored material is squeezed out, leaving only that which is in the depressions to be deposited on the under side of the web to form the design or colored pattern together with a lighter color background on the intermediate portions. The web then passes around a dryer I, preferably a non-revolving steam heated drum which contacts only with the uncolored surface of the paper. The extent 10 of the surface in contact with the dryer may be varied by means of a roller J which is adjustable around the periphery of the drum I as indicated by the arrows in dotted lines. After passing around the roller J the web is delivered to the 20 rewinder, not shown.

The paper web in passing around the resilient surface of the roller F is held in close sealing contact therewith so as to prevent the running of the coloring material on to the reverse side of the 25 paper. However, as illustrated in Fig. 3, the portions of the roller F which extend beyond the edges of the paper strip will come in contact with the coloring material carried by the roller G which will be transferred thereto and carried upward. This might result in smearing the reverse surface of the paper as it passes around the roller E and to avoid such effect I preferably blow compressed air into the trough between the rollers F and E and direct it outward from the edges 35 of the paper strip, as shown at H and H' in Fig. 3. This will clear the surface of the roller F from the coloring material in the vicinity of the edges of the sheet, not only preventing it from smearing the reverse side of the paper strip but also avoiding any danger of the sticking of the edges of the strip when rewound, which might render it difficult to afterwards unroll. However, the process may be carried out without the use of these air jets.

When an engraved roller is used on which a pattern is engraved, the effect of operating in this manner is to produce a two-color effect. The unengraved portions of the copper roller give a light coloring effect, and the deeper engraved 50 portions give a deeper effect of color. After the paper is colored, it is then dried by passing the web over a cylindrical drier or series of dryers, and in this operation it is important that the colored surface does not come in contact with any 55 roller or other object until it is dry, otherwise the color will smear. Having accomplished the drying, the paper is then rewound into a roll.

It is possible to employ a multi-color effect in this process by passing the paper with one color 60 application through a similar set of rollers, using a pattern which registers with the first, and which employs a second color. It is also possible to adapt other forms of continuous printing to the paper after the first application of color, such as by aniline printing, by means of raised rubber dies on a roller, using quick drying alcohol soluble aniline dyes.

Among the materials employed, for a solid plain color, a solution of aniline dye in water, to which 70 some alcohol has been added may be used. Or, for a similar solid color effect, a water solution of an aniline dye to which a solution of casein has been added will produce a plain effect. For design effects, it has been found desirable to 75

thicken the color solution by adding some water soluble material, such as casein, starch or animal glue, with or without clay, lithopone, zinc pigments, titanium oxide or other similar solid materials, depending on the surface effects desired.

To produce proper coloring, the absorbent character of the paper surface and the penetrating character of the coloring matter must be regulated with respect to each other. I have found that the subjection of the paper surface to a steam bath places it in condition to receive more uniformly the coloring material. With certain papers and with certain water soluble aniline dyes it may be desirable to mix with the coloring material alcohol or some other substance for increasing the penetrating power. Again, for other uses it may be desirable to increase the viscosity of the coloring material so as to lessen the penetrating power, and again for certain uses an adhesive constituent such as casein may be advantageously added to the coloring matter. By such regulation different effects may be produced as desired.

What I claim as my invention is:

1. A process of coloring paper comprising the feeding of a paper strip between a knurled roller and a roller having a resilient surface flooding the surface of the knurled roller and the paper surface adjacent thereto with coloring material whereby in the movement of the paper between said rollers surplus coloring material is squeezed out and the color in the indentations of the roller is deposited on the surface of the paper and after separating from the paper removing all coloring material from the portions of the resilient roller which are adjacent to the edges of the paper subsequently contacting with the roller.

2. The process of coloring paper comprising the feeding of a paper strip around a segment of a roller having a resilient surface and between said roller and a knurled or engraved roller, flooding the surface of said knurled roller and the paper adjacent thereto with coloring material whereby in the passing of the paper strip between said

roller surplus coloring material will be squeezed out and the coloring material in the indentations of the knurled or engraved roller will be deposited on the surface of the paper and after separating from the paper removing all coloring material from the portions of the resilient roller which are adjacent to the edges of the paper subsequently contacting with the roller.

3. The process of coloring paper comprising the feeding of a paper strip between a knurled or engraved roller and a roller having a resilient surface, flooding the surface of the knurled roller and the surface of the paper adjacent thereto with coloring material whereby in the passing of the strip between said rollers surplus coloring material is squeezed out and coloring material in the indentations of the roller is transferred to the surface of the paper, and blowing the coloring material adhering to the portions of the resilient roller adjacent to the edge of the paper to remove the same from further contact with the paper.

4. In a process of coloring paper by feeding the same in contact with a knurled or engraved roller flooded with coloring material, the step of adjusting in relation to each other the absorptive property of the paper surface and the penetrating quality of the coloring material.

5. In a process of coloring paper by feeding the same in contact with a knurled or engraved roller flooded with coloring material, the step of humidifying the surface of the paper in advance of the contact of the same with the coloring material.

6. In a process of coloring paper by feeding the same in contact with a knurled or engraved roller flooded with coloring material, the step of treating the surface of the paper with steam in advance of contacting the same with the coloring material.

7. In a process of coloring paper by feeding the same in contact with a knurled or engraved roller flooded with coloring material, the step of adjusting the viscosity and penetrating characteristic of the coloring material with respect to the absorptive characteristic of the paper.
